x Inventor,

*Walter Althoff,
J.W. Dahm,
Attorney.*

UNITED STATES PATENT OFFICE.

WALTER ALTHOFF, OF BOCKENEM-ON-THE-HARZ, GERMANY.

VAT FOR WASHING FIBER MATERIAL AND THE LIKE WOUND ON BOBBINS.

Application filed June 20, 1927, Serial No. 200,217, and in Germany April 18, 1927.

My invention relates to improvements in vats for washing fiber material and the like wound on bobbins, and the object of the improvements is to provide a vat in which the liquid supplied to the vat is drawn by suction through the bobbins from the outside to the inside thereof, so that washing is completed within a minimum of time.

For the purpose of explaining the invention several examples embodying the same have been shown in the accompanying drawing, in which the same reference characters have been used in all the views to indicate corresponding parts. In said drawing,

Fig. 1, is a sectional elevation showing my improved vat,

Fig. 2, is a top plan view of Fig. 1, and

Figs. 3 to 5, are detail sectional elevations showing parts of vats of modified constructions.

In the example shown in Figs. 1 and 2 the vat comprises a bottom *a* pressed into concave form and having a discharge opening *b*, a horizontal partition *c* formed with apertures *i*, and side walls *d* supported on said partition. The said parts are internally coated with a medium resistant to acids and alkalis such as caoutchouc, and they are jointed with one another by means of screws and nuts, a suitable packing medium being placed between the said parts, if necessary. The side walls *d* may be provided with openings for admitting or discharging the liquid. But I wish it to be understood that in some cases the liquid is poured into the vat through the open top thereof. To the bottom *a* two uprights *g* in the form of bridges are fixed which provide a support for the partition *c* and thus resist the strains exerted on the said partition by the vacuum produced below the same.

On the partition *c* and around each opening *i* a ring *k* of soft caoutchouc or similar packing medium is placed, and the said ring may be connected with the acid proof coating of the partition. The bobbins *m* having the fiber material wound thereon are placed on the said ring for being washed within the vat, and further bobbins *m* may be placed on the lowermost set of bobbins, packing rings *n* and *o* made from soft caoutchouc being placed between the superposed bobbins. In

Fig. 1 I have shown two superposed bobbins, but I wish it to be understood that any suitable number of bobbins may be placed one above the other so far as is permitted by the height of the vat. The uppermost bobbins are closed by means of plates *p* and packing rings *n*. The outlet *b* of the vat is connected by a pipe with a suitable pump adapted to withdraw the liquid and to produce a vacuum below the partition *c* and within the bobbins placed thereon.

By the suction of the pump the washing liquid is drawn from the upper section of the vat through the layer of fiber material and holes made in the walls of the bobbins and into the inner parts of the said bobbins, from whence it flows through the apertures *i* made in the partition *c* and into the bottom part of the vat and the pipe connected with the pump.

In the modification shown in Fig. 3 the vat is provided with a flat bottom *q*, and the partition *r* is provided with a downwardly directed flange *r'* bearing on and fixed to the bottom *q*.

Further, the partition *s* may be made integral with the bottom *t* of the vat, as is shown in Fig. 4, in which case however, the discharge opening *u* must be sufficient in size to permit access to the chamber provided between the bottom *t* and the partition *s* for coating the said parts with an acid and alkali proof coating.

In Fig. 5 I have shown a modification in which the partition *v* is made integral with the side walls *w* of the vat, and the bottom *x* is formed with an upwardly directed flange *y* on which the side walls *w* and the partition *v* are supported. In another modification a concave bottom is used, as is shown in Fig. 5 in dotted lines.

I claim:

A device for washing fibrous material wound on bobbins comprising a vat having walls internally lined with a layer of caoutchouc and having outwardly projecting flanges at the bottom, a perforated partition in said vat lined above and below with layers of caoutchouc, packing rings resting on said partition about the perforations to support bobbins in fluid-tight relation to the partition, a bottom member lined with a layer of

caoutchouc, said member providing with the partition a closed chamber having an outlet for washing fluid entering through said perforations, and having sides provided with flanges bearing against projecting parts of said partition whereby the partition and the flanges above and below the same may be bolt-

ed together, and bridges on said bottom member supporting the partition adjacent the middle of the same the packing rings being 10 fixed to the lining of the partition.

In testimony whereof I have affixed my signature.

WALTER ALTHOFF.
